US0D1072720S

(12) **United States Design Patent** (10) **Patent No.:** **US D1,072,720 S**
(45) **Date of Patent:** **** Apr. 29, 2025**

(54) **TIRE VALVE COMPONENT**

(71) Applicant: **Clik Corporation**, Westlake Village, CA (US)

(72) Inventor: **John Quintana**, Camarillo, CA (US)

(73) Assignee: **Clik Corporation**, Westlake Village, CA (US)

(**) Term: **15 Years**

(21) Appl. No.: **29/832,914**

(22) Filed: **Mar. 30, 2022**

CLAIM

The ornamental design for a tire valve component as shown and described.

DESCRIPTION

FIG. 1 is a front view of an ornamental design for a tire valve component, showing my new design;

FIG. 2 is a back view of the ornamental design for a tire valve component shown in FIG. 1;

FIG. 3 is a right side view of the ornamental design for a tire valve component shown in FIG. 1; and,

FIG. 4 is a left side view of the ornamental design for a tire valve component shown in FIG. 1.

The ornamental design for the tire valve component may be used, for example, with bicycle tires, etc.

1 Claim, 4 Drawing Sheets
